Howson and Howson

UNITED STATES PATENT OFFICE

WILLIAM J. MASSA, OF NEW YORK, N. Y., ASSIGNOR TO BERGEN POINT IRON WORKS, OF BAYONNE, NEW JERSEY, A CORPORATION OF NEW JERSEY

EXPANSION JOINT FOR FLUE SECTIONS AND THE LIKE

Application filed October 29, 1929. Serial No. 403,271.

This invention relates to improvements in expansion joints for flue sections and the like irrespective of the cross section of the flue or like conduit to which the invention is applied. In the past it has been customary to construct expansion joints with either curved or angular corrugations which permit expansion of the flue by distortion of the shape of the corrugations of the joint. This type of expansion joint has been found undesirable for the reason that ultimately the joint fails or becomes ruptured, especially at the corners when the joint is used in flues of square or any like cross-section having corners.

It is the principal object of my invention to provide a gas tight expansion joint applicable to flues irrespective of their cross section, this joint to be constructed so as to allow the flue to expand and contract without flexure or rupture of any of the parts comprising the expansion joint. Other objects of my invention will appear as my invention is described in connection with the accompanying drawing.

In the drawing

Figure 1 is a foreshortened elevation sectional view of an expansion joint constructed according to the principles of my invention and shown in cooperating relation with two adjoining flue sections. The view is taken on a section passing longitudinally through the flue.

Figure 2 is a foreshortened sectional or plan view of my invention as shown in Figure 1 with the section taken on line 2—2 of Figure 1.

Figure 3 is a fragmentary elevation sectional view showing in section one side of a modified construction of my expansion joint.

Referring to the drawing it will be noted that the invention is applied between two adjoining flue sections 10 and 12 of square cross section. At the ends of the flue sections and around the periphery thereof continuous right angle members 14 and 16 are bolted or riveted with one flange of the angles flush with the ends of the section and the other flange extending out perpendicularly to the flue. In order that the expansion joint may

be secured to the flue sections I provide angle members 18 and 20 on the expansion joint which are similar in size and cross section to angles 14 and 16 and cooperate therewith as will now be described. These angles 18 and 20 are positioned with one of their flanges, A, A' lying parallel to the outwardly extending flanges of the angles 14 and 16. The other flanges B, B' of the angles 18 and 20 project onward from the flue sections parallel to the axis thereof. To join these projecting flanges B, B' of the angles 18 and 20 and to keep the gases from escaping, while at the same time allowing for expansion and contraction between the flue sections, I provide a sleeve 22 of substantially the same dimensions in cross section as the flue sections. This sleeve may be bolted or riveted to the projecting flange B of the angle 18 and may be slidably connected with the projecting flange B' of the angle 20 by bolts 25 passing through slots 26 in the sleeve 22. In this way the movement of the sections toward and away from each other is limited and the sections are permanently connected.

To insure a tight seal between the angles 18 and 20 I provide a member 28 which at its center is bowed outwardly from the axis of the flue while its edges lie parallel with the projecting flanges B, B' of the angles 18 and 20. I prefer to make this member of resilient material so that it may be put under spring tension by means hereinafter described. One edge of this resilient member may be secured to the projecting flange B of the angle 18 by the same bolts or rivets which secure the sleeve 22 to this flange. The other edge of this resilient member 28 is provided with a piece of gasket material 29 riveted to it all the way around its edge, between the edge and the flange B against which it presses, to provide a seal between the edge and the flange B'. It will be noted, since this gasketed edge is not secured to the projecting flange of the member 20 that there may be a relative movement between this gasketed edge and the flange B' during expansion and contraction of the flue section. In order to make this sliding connection tight, I provide bolts 30 transverse to the flue axis and passing

100

through the sleeve 22 between the ends of the projecting flanges B, B' and through the center of the resilient member 28. Upon screwing the nut 32 on to the bolt 30 the resilient member 28 may be caused to press with more or less force against the flange B' and the transverse bolts 30 may be put under tension and the amount of tension applied may be varied to suit the requirements of the particular conditions of use.

In Figure 3 I have shown a modified form of my invention. In this modification an angle 14' similar to the angle 14 hereinbefore described, is secured to the flue section 10'. This angle 14' has secured to it by bolts or rivets an angle 18' similar to the angle 18 hereinbefore described. A sleeve member 22' similar to sleeve 22 may be secured to the angle 18' in the same way that sleeve 22 is secured to the angle 18. This sleeve 22' is adapted to slide along inside of an adjoining flue section 12', a gasket 36 being inserted between the sleeve 22' and the flue section 12' in order that a tight joint might be made and that the sleeve may still be able to slide within the flue.

Bridging the gap between angle 18' and the end of the flue section 12' is a bowed member 28' similar to the member 28 hereinbefore described. The edges of this bowed member lie parallel with the leg B of the angle 18' and with the flue section 12'. Gaskets 29' may be riveted to these bent edges to prevent escape of gases between the engaging surfaces of the bowed member with the flue section 12' and with the leg B and the angle 18'.

The member 28' may, if desired, be made of resilient material and it may be secured in assembled position (see Figure 3) and put under stress by means of bolts 30' passing transversely through apertures in the end portion of the flue section 12' and through the center of the bowed member 28' as in the case of Figs. 1 and 2. In order that the head of the bolt 30' will not obstruct the movement of the sleeve 22' and the section 12' relative to each other the head of the bolt is countersunk in the flue section 12' as shown.

Resilient means are provided to secure the adjoining flue sections 10', 12' together and limit their movement apart. This means may consist of a plurality of rods 40 running parallel to the flue axis outside the expansion joint. These rods slide through apertures in the angle 18' and through apertures in the angle member 16' which is secured to the flue section 12' by bolts or rivets. To allow limited movement of the sections away from each other and to restrain that movement the rods 40 are made longer than the distance between the angles 18', 16' and compression springs 41 are coiled around the rods between nuts 42 on the ends of the rods and the angles 16', 18' respectively. Similar springs 43 are coiled around the rod between the

angles 16', 18' respectively and a sleeve 44 located on the rod 40 at its center whereby the movement of the sections toward each other is restrained and limited.

It will be noted that the function of the resilient means just described is similar to that of the bolts 25 and slots 26 shown in Figures 1, 2.

From the foregoing it is apparent that I have provided a joint which does not employ any element which is subject to continued bending or flexure. Thus I have provided a joint which will not fail due to rupture or cracking of any member and at the same time I have provided a joint which though gas tight, allows free movement to the flues for expansion and contraction.

While I have shown my invention as applied to a square flue it will be obvious that the invention is equally applicable to flues of other shapes and is not in any way limited in application to a square flue.

Many changes within the scope of my invention will occur to those skilled in the art therefore I do not limit myself to the specific embodiments shown.

I claim:

1. An expansion joint for flue sections and the like comprising a bowed member adapted to be located between the ends of flue sections to prevent the escape of gases, and means transverse to the axis of the flue to apply and vary pressure on said bowed member, whereby to make a tight joint.

2. An expansion joint for flue sections and the like comprising a bowed member adapted to be located between the ends of flue sections to prevent the escape of gases, and means transverse to the axis of the flue to hold said bowed member in fixed relation to one of the flue sections while allowing said member to have sliding relation to the other flue section.

3. An expansion joint for flue sections and the like, comprising members adapted to be secured to adjoining flue sections, a sleeve member rigidly connected at one end with one of said first mentioned members and slidably engaging at its other end with another of said first mentioned members, a member bridging the gap between said first mentioned members, and means positively holding said last mentioned member against said first mentioned members.

4. An expansion joint for flue sections and the like, comprising members adapted to cooperate with adjoining flue sections, a member rigidly connected at one end with one of said first mentioned members and slidably connected at the other end to another of said first mentioned members, a member bridging the gap between said first mentioned members, and means transverse to the flue axis to apply and vary pressure on said bridging member.

5. An expansion joint for flue sections and the like, comprising members adapted to be secured to adjoining flue sections, a sleeve member rigidly connected at one end with one of said first mentioned members and slidably connected at the other end to another of said first mentioned members, and a member bridging the gap between said first mentioned members, said bridging member being rigidly secured to one of said first mentioned members and slidably engaging another of said first mentioned members, and means transverse to the flue axis to apply and vary pressure on the resilient member.

10 6. An expansion joint for flue sections and the like, comprising members adapted to co-operate with adjoining flue sections, a member rigidly connected at one end with one of said first mentioned members and slidably engaging at the other end with another of said first mentioned members, a member bridging the gap between said first mentioned members and means transverse to the flue axis to apply and vary pressure on said bridging member.

15 7. An expansion joint for flue sections and the like, comprising members adapted to co-operate with adjoining flue sections, a sleeve member rigidly connected at one end with one of said first mentioned members and slidably connected at the other end to another of said first mentioned members, a member bridging the gap between said first mentioned members and transverse bolts passing through said bridging member, to apply and vary pressure on said bridging member.

20 8. An expansion joint for flue sections and the like, comprising members adapted to be secured to adjoining flue sections, a sleeve member rigidly connected at one end with one of said first mentioned members and slidably connected at the other end to another of said first mentioned members, a resilient member bridging the gap between said first mentioned members, said resilient member being rigidly secured to one of said first mentioned members and slidably engaging another of said first mentioned members, and means transverse to the flue axis to apply and vary the tension in the resilient member, said means passing through said sleeve member and said resilient member.

25 9. The combination with a plurality of flue sections, of an expansion joint comprising a member secured to one of said sections, a member associated with an adjoining section, resilient means bridging the gap between said members, and means transverse to the flue axis to apply and vary pressure on said resilient member.

30 10. The combination with a plurality of flue sections of an expansion joint comprising a member adapted to be secured to one flue section, a second member rigidly secured to the first named member, a third member en-

gaging with an adjoining section, said second member having sliding engagement with said third member, and a resilient member bridging the gap between said third member and said second member, and means transverse to the flue axis to apply and vary pressure on said resilient member.

35 11. The combination with a plurality of flue sections, of an expansion joint therebetween comprising an angle member adapted to be secured to one section, means engaging with an adjoining section, a sleeve member secured to said angle member and engaging slidably with said means, together with a resilient member bridging the gap between said means and said angle member, and means transverse to said sleeve member and passing through said resilient member to apply and vary pressure on said resilient member.

40 In testimony whereof I have signed my name to this specification.

45 WILLIAM J. MASSA.
